CLAIM

The ornamental design for an equipment for distribution of electric power, as shown and described.

DESCRIPTION

FIG. 1 is a perspective top, front and left side view of an equipment for distribution of electric power showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a rear view thereof; and,

FIG. 8 is a perspective top, rear and right side view thereof. The broken line portion of the figure drawings is included to show unclaimed subject matter only and forms no part of the claimed design.

1 Claim, 8 Drawing Sheets
